UNITED STATES PATENT OFFICE.

SHINATARO IMAMURA, OF NISHIKU, NAGOYA, JAPAN.

MECHANICAL STOKER.

Application filed September 23, 1924, Serial No. 739,419, and in Japan October 1, 1923.

My invention relates to improvements in a mechanical stoker and has for its object to provide a simple, effective and economical stoker.

5 According to the present invention grate bars are transversely arranged to form a series of fuel supporting shelves in stepped relation at a suitable inclination with air openings between said grate bars to supply air 10 horizontally from the under side of the grate. Reciprocating pusher members are provided for each step of the grate bars and are slowly operated by a suitable reciprocating mechanism through said air openings 15 whereby the fuel supplied from the hopper is burned on the grate while being gradually conveyed on the steps. The upper surfaces of each grate bar are arranged in a plane, but for the sake of strength as well as for increasing the grate surface, the grate bars are 20 preferably corrugated and the sliding members of triangular cross section are arranged to slide on the bottom or trough parts of said corrugations through circular openings 25 formed on the ribs projecting at the lower sides of the grate bars. Such corrugated bars are arranged in such a manner that the top of a corrugation of one grate bar is in vertical alignment with the troughs of the 30 adjacent bars so that when the fuel falls from the bottom parts of the upper step it strikes ridges of the lower step and while said fuel is falling into the troughs of the next lower bar it is rolled or overturned and 35 the combustion is thereby accelerated.

While it is known to be old in the prior art to provide grates whose surfaces are stepped and over which the fuel is gradually conveyed while burning, the present invention 40 is characterized in that sliding members connected to a reciprocating mechanism are provided for each of the steps of the grate and the fuel on each step is simultaneously transported to the lower step and is 45 burned by air supplied horizontally from the air openings formed in ribs on the under sides of the bars. The fuel falls on the lower step while the sliding member is going forward on said step and the air opening is 50 partially closed by the sliding member. When the sliding member moves backward the fuel remains on the grate bar being agitated by the movement of the sliding member and the air opening is fully opened while 55 the sliding member rests at its backward

position, thus the combustion of the fuel is accelerated and a considerable economy of fuel is obtained.

The accompanying drawing shows an example of the mechanical stoker embodying the present invention. Fig. 1 is a sectional side elevation of the stoker as applied to a boiler furnace. Fig. 2 is an enlarged elevation of the stoker as seen from within the furnace. Fig. 3 is a sectional side elevation of the structure shown in Fig. 2, also showing in section the connections between some of the pusher members and the transverse bars.

In Fig. 1, (1) is the wall of the furnace, (2) is a boiler; (3) is a hopper for receiving coal, (4) are grate bars or fuel supporting shelves arranged transversely keeping a suitable clearance between adjacent bars to form a stepped grate of some thirty degrees or less inclination. Said grate bars may be made in the form of thin plates, but as they are apt to become deformed owing to the elongation and contraction caused by the temperature of combustion, their upper sides are preferably corrugated as shown in Fig. 2, whereby the deformation can be avoided and at the same time the surface area of the grate increased. Such corrugated bars are arranged in such a manner that the ridges of one grate bar are in vertical alignment with the troughs of the adjacent grate bars as shown in Fig. 2 so that the fuel falling from the troughs of the upper step is divided by the angular ridges of the lower step and rolls into the troughs thereof. Each grate bar (4) is provided at its lower side with a strengthening rib (5) and circular openings (6) for the supply of air are formed in said rib in horizontal alignment with the troughs of the next lower step.

The sliding members consist in rods of substantially triangular section passing freely through the air openings (6) thus leaving some clearance for the passage of air. The other ends of these rods (7) are connected by pins (8) to transverse bars (9) fixed at both ends to a frame (10) corresponding in inclination to the steps in inclination of the grate. The frame (10) is mounted on rollers 12 which roll on the rail (11) and is connected by a rod (13) to a crank (14) which is slowly rotated by a worm mechanism (15).

The width of the grate bars and the num- 110

ber of steps of the grate are properly de-
signed so that the fuel is completely burned
while being conveyed to the lowermost step.
The quantity of the fuel to be supplied on
5 the grate can be adjusted by regulating the
speed or number of reciprocations of the slid-
ing member (7). An ordinary fixed grate
(16) is arranged at the lower end of the
stepped grate for thoroughly burning any
10 fuel into ash. As the volume of the fuel less-
ens while burning on the stepped grate, the
grate bars are preferably made broader to-
ward the lower steps, as shown in Fig. 3.
Slots (17) are formed in the sliding mem-
15 bers (7), at the lower steps, the length of
the slots being gradually increased towards
the bottom of the grate so that the lengths
of the strokes of the sliding members for the
lower steps are gradually diminished as the
20 quantity of fuel conveyed is lessened. How-
ever, the device may use either the fixed or
slotted connection with all the pusher mem-
bers.

I claim:—

- 25 1. In a mechanical stoker, in combination,
a plurality of fixed fuel supporting shelves
in stepped relation, each of said supporting
shelves being provided with troughs, the
troughs of each shelf being in staggered re-
30 lation to the troughs in the adjacent shelves,
pusher members adapted to reciprocate in
said troughs, and means for reciprocating
said pusher members.
2. In a mechanical stoker, in combination,
35 a plurality of fixed grate bars in stepped re-
lation, each of said bars being provided with
transverse troughs, the troughs in each bar
being in staggered relation to the troughs in
the adjacent bars, pusher members adapted

to reciprocate in said troughs, and means 40
for reciprocating said pusher members.

3. In a mechanical stoker, in combination,
a plurality of fixed grate bars in stepped re-
lation, each of said bars being provided on
its upper side with transverse troughs and 45
on its lower side with a longitudinal rib,
the troughs of each bar being in staggered
relation to the troughs in the adjacent bars,
air openings in said ribs, pusher members
extending through said openings and adapt- 50
ed to reciprocate in the troughs of the adja-
cent bar, and means for reciprocating said
pusher members.

4. In a mechanical stoker, in combination, 55
a plurality of fixed fuel supporting shelves
in stepped relation, each of said supporting
shelves being provided with troughs, the
troughs of each shelf being in staggered re-
lation to the troughs in the adjacent shelves, 60
pusher members adapted to reciprocate in
said troughs, and a reciprocating frame to
which said pusher members are connected,
whereby said pusher members are given a reciprocating motion.

5. In a mechanical stoker, in combination, 65
a fuel hopper, a plurality of fixed grate bars
in stepped relation, each of said bars being
provided with transverse troughs, the
troughs of each bar being in staggered re-
lation to the troughs in the adjacent bars, the 70
width of said bars successively decreasing to-
wards the fuel hopper, pusher members
adapted to reciprocate in said troughs and
means for reciprocating said pusher mem-
bers. 75

In testimony whereof I have affixed my
signature.

SHINATARO IMAMURA.
